UNITED STATES PATENT OFFICE.

JOHN E. CASE, OF NEW YORK, N. Y., ASSIGNOR TO ATHENS SHIPBUILDING CORPORATION, OF NEW YORK, N. Y.

DESIGN FOR A BURIAL-CASKET.

56,096.

Specification for Design.

Patented Aug. 17, 1920.

Application filed February 21, 1920. Serial No. 360,394. Term of patent 7 years.

To all whom it may concern:

Be it known that I, JOHN E. CASE, a citizen of the United States, residing at New York city, in the county of New York and State of New York, have invented a certain new, original, and ornamental Design for Burial-Caskets, of which the following is a specification, reference being had to the accompanying drawing, forming part thereof.

Figure 1 is a top plan view of a burial casket, showing my new design.

Fig. 2 is a side view of the same.

I claim:

The ornamental design for a burial casket, as shown.

JOHN E. CASE.
